RADIATOR VALVE

William B. Mackintosh, Wabash, Ind., assignor to
Minneapolis-Honeywell Regulator Company,
Minneapolis, Minn., a Corporation of Delaware

Application May 19, 1930. Serial No. 453,611

7 Claims. (Cl. 236—42)

The present application relates, as indicated, to radiator valves, and more particularly to thermosensitive valves for controlling the flow of a heating fluid to a radiator. The primary object 5 of the invention is to improve and simplify the construction of valves of this type, the improvements in the present instance residing primarily in refinements of construction. Further objects of the invention will appear as the description 10 proceeds.

In the drawing Fig. 1 is a vertical sectional view through an embodiment of my invention;

Fig. 2 is a section taken substantially upon the line 2—2 of Fig. 1;

Fig. 3 is an end elevation of a block comprising an element of the disclosed valve; and

Fig. 4 is a sectional detail taken substantially upon the line 4—4 of Fig. 1.

Referring more particularly to the drawing, it 20 will be seen that the valve of the present application comprises a casing 1 of the ordinary angle type and having an externally threaded neck 2 with which is threadedly engaged a hub 3 having an inwardly extending annular flange 4 providing 25 a swivel engagement with a collar 5. A disc 6 is clamped to said collar 5, the outer end of said collar being spun over said disc as at 7 to hold the same in place.

Engagement of the hub 3 with the neck 2 of 30 the casing 1 clamps between the outer end of said neck and said collar 5 a ring 8 to which is sealed one end of a bellows 9, the opposite end of said bellows being sealed to a ring 10 rigidly secured to a valve cup 11 carrying a valve head member 12 for cooperation with a seat 15 formed in said casing 1. Said valve cup 11 is formed with a 35 central threaded stud 14 on which is threadedly engaged a spider or guide 13 snugly slidable within the outlet port.

A shell 16 has its inner open end secured to the periphery of disc 6 by means of screws 17 or other suitable fastening means, and has its outer end closed by a disc 18 abutting an internal head 50 and secured in place by soldering or other means.

An apertured plate 19 is received in said shell in abutting relation with a second internal head 20 and forms a retaining abutment for one end of a coil spring 21, said spring end being centered by 50 means of a spring guide 22. The opposite end of said spring is received in a spring seat 23 mounted upon a plate 24 which plate seals one end of a bellows 25, the opposite end of which is sealed to an annulus 26 located between said plate 19 and an internal shoulder 51, formed in said shell

16. Preferably, said annulus 26 is soldered in place.

A projection 27, having internal threads 28, is secured to valve cup 11 by means of fingers 27' projected through perforations in plate 10 and cup 11 and soldered in place.

A similar internally threaded projection 29 is secured to the forward face of the plate 24 by means of fingers 29' inserted through perforations 24' in said plate and headed over, as shown. The 65 threads of said projection 29 are of the opposite hand with respect to the threads 28.

An adjusting stem is indicated generally at 30 and comprises a section 31 provided at its one end with a threaded head 52 for cooperation with the 70 threads 28 of the projection 27 and at its opposite end with a reduced threaded extension 33; and a section 32 comprising a threaded head 53 for co-operation with the threads of the projection 29 and a reduced threaded extension 34. As will be 75 obvious, the threads of the head 53 are of the opposite hand with respect to the threads of the head 52.

A gear 35 is formed with a bore 54 threaded for the reception of projections 33 and 34 and is 80 conveniently soldered or welded to the stem sections 31 and 32 after the initial assembly, the parts being made in three pieces for convenience of manufacture.

The shell 16 is formed with a slot 36 in its periphery and the disc 6 and plate 19 are formed with shallow registering radial slots or notches 56 and 37 respectively, for the reception of a pivot pin 39 on which is mounted an actuating lever 38. A plate 40 partially covers the slot 36 but permits 90 oscillation of the lever 38 about its axis. The outer end of the lever 38 is formed as a hand grasp, while the inner end thereof is formed as a gear sector having teeth 57 meshing with the gear 35.

The closure plate 18 is centrally provided with a nipple 41 having a bore therethrough and formed with internal and external screw threads. A block 42 of insulating material is mounted on the outer end of the shell 16 and, as is shown most clearly in Figs. 1 and 3, the inner face of said block is castellated or formed with a plurality of intersecting radial slots to permit air circulation between said block 42 and said plate 18. Said block 42 is formed with a bore shaped, at 58, to 105 conform to said nipple 41, whereby said block is centered on said shell.

A chamber 43 of annular form is mounted in embracing relation with a reduced extension 59 on said block 42 and is retained in place by a 110

screw 44 of heat insulating material threaded into said block 42. Said block 42 is formed with a helical groove 60 in which is mounted a tube 45, one end 61 of said tube being in communication 5 with the interior of the chamber 43, and the opposite end 62 of said tube opening through the plate 18 into the chamber 46 formed by the shell 16, the plate 18, and the bellows 25 with its sealing plates 24 and 26. The nipple 41 provides a 10 charging opening for the chamber comprising said chamber 46, the tube 45 and the chamber 43; and the bore of said nipple 41 is adapted to be closed, after charging by a screw plug 47. A nut 48 threaded on the external threads of the 15 nipple 41 retains the block 42 in place on said shell 16.

The manner of mounting the container 43 and the tube 45 is an important feature of the present invention. The end 62 of the tube is first 20 positioned and soldered in place in the aperture in the plate 18. Thereafter, the tube end 61 is secured in the aperture in the container 43 and, said container not having been positioned on the projection 59, the tube 45 is laid in the convolutions of the groove 60. As such laying nears completion, the container 43 is drawn by the tube into proximity with the projection 59. The container 43 is now positioned on the projection 59, the end 61 of the tube falling into the slot 63 which, it 25 will be understood, has a peripheral width materially greater than the diameter of the tube 45. The screw 44 is now started in the bore 64, but is not turned down onto the container 43 until the latter has been rotated somewhat about its 30 axis to tighten the tube 45 in its groove 60.

While I have shown and described a slot 63 receiving the tube end 61, it will be obvious that many of the advantages of this arrangement could be attained by providing in the base of the 40 container 43 a radial groove of sufficient axial depth to accommodate the tube end 61, whereby rotation of the container 43 with respect to the block 42 would be permitted.

Another manner in which the parts of the 45 device may be assembled is as follows: The end 61 of the tube 45 is soldered in place in the aperture in the container 43. The container 43 is then mounted on the projection 59, and the screw 44 is turned down to clamp the container 50 in place. The tube 45 is then wrapped about the block 42, being received in the groove 60, the length of said tube being such as to provide a portion 4 to 6 inches long projecting from the final convolution of the groove. This portion is inserted 55 between the castellations of the block 42 and, said block not having been mounted on the shell 16, the end 62 of the tube is soldered in place in the opening in the plate 18. Thereafter, the block 42 is positioned on the end of the shell 60 16, the slack of the tube 45 being received between said block and the plate 18, and said block is secured in place by the nut 48.

In operation, the valve casing 1 being connected 65 in the supply line to a radiator, the operating handle 38 is oscillated about its pivot 39 to a desired position, such oscillation rotating the stem 30 through the coaction of the teeth 57 with the gear 35. The threaded projections 27 and 29 being held against rotation, such rotation of the 70 member 30 results in adjustment of the valve member 12 and the plate 24 with respect to each other, thereby adjusting the degree of compression of the spring 21 required to close the valve. If the temperature in the room in which the 75 valve is mounted is below that for which the

mechanism is calibrated at the selected setting of the handle 38, such setting of the handle 38 results in withdrawal of the valve 12 from its seat 15 through the action of the spring 21. Heating fluid thus flows to the radiator until the 80 temperature of the room is brought to the desired value. Such increase in the temperature of the room results in the expansion of the thermo-sensitive fluid in the chamber 46, tube 45 and chamber 43, whereby the bellows 25 is collapsed, overcoming the tendency of the spring 21, and the valve 12 is moved to its seat 15 to stop 85 flow of heating fluid to the radiator.

The most efficient thermo-responsive fluid for 90 use in this device is a readily volatilized liquid, the gas from which fills chamber 46 and the major volumes of tube 45 and chamber 43, a small surplus of the liquid being maintained in chamber 43.

I claim as my invention:

1. In a device of the class described, a valve 95 casing providing an inlet, an outlet, and a valve seat therebetween, a valve in said casing for co-operation with said seat, a stem having a threaded connection with said valve, a collapsible and expansible chamber, a bellows forming one wall of said chamber, a spring seat connected to said bellows, a spring abutment stationarily mounted in said casing, said stem having a threaded connection with said spring seat, a spring restricted 100 between said spring seat and said abutment, means for causing relative rotation between said stem and said valve and spring seat, a block of heat insulating material secured to said casing, 105 a container mounted on the side of said block removed from said casing, and a tube providing communication between said container and said chamber.

2. In a device of the class described, a valve 110 casing providing an inlet, an outlet, and a valve seat therebetween, a valve in said casing for co-operation with said seat, a stem having a threaded connection with said valve, a collapsible and expansible chamber, a bellows forming one wall of said chamber, a spring seat connected to said bellows, a spring abutment stationarily mounted in said casing, said stem having a threaded connection with said spring seat, a spring restricted 115 between said spring seat and said abutment, peripherally spaced teeth on said stem intermediate 120 its ends, a gear sector pivoted in said casing and meshing with said teeth for rotating said stem, and means for preventing rotation of said valve 125 and spring seat.

3. In a device of the class described, a valve 130 casing providing an inlet, an outlet, and a valve seat therebetween, a valve in said casing for co-operation with said seat, a stem section threaded 135 and engaged, at its one end with said valve and formed at its opposite end with a reduced threaded extension, a collapsible and expansible chamber, a bellows forming one wall of said chamber, an internally threaded hub secured to said bellows, a stem section threadedly engaged, at its 140 one end, in said hub and formed at its opposite end with a reduced threaded extension, the first-mentioned threads on said second stem section being of the opposite hand from the first-mentioned threads on said first stem section, an internally threaded gear receiving said reduced 145 threaded extensions, and a toothed member oscillably mounted in said casing and meshing with said gear for rotating said stem sections simultaneously.

4. In a device of the class described, a valve 150

- casing providing an inlet, an outlet, and a valve seat therebetween, a valve in said casing for co-operation with said seat, a stem on said valve, resilient means engaging said stem and urging 5 said valve away from its seat, and means for moving said valve against the tendency of said spring, said last-mentioned means comprising a shell forming a chamber having its one end closed by a plate and its opposite end closed by a bellows engaging said stem, a block of heat insulating material mounted on said shell adjacent said plate, a container secured to the free face of said block, and a tube connected at its one end to said container and at its opposite end to said 10 chamber, said tube having its intermediate portion wound about the surface of said block. 15 5. Thermo-responsive actuating means comprising a shell forming a chamber having its one end closed by a bellows and its opposite end closed by a plate, a block of heat insulating material secured to the latter end of said shell and having a portion of its adjacent surface spaced from said plate, a container mounted on the free face 20 of said block, and a tube having its one end received in a space between said block and said container and entered in said container, and having its intermediate portion wound about said block, and having its opposite end inserted in the space 25 between said block and said plate and entered in an aperture in said plate. 30 6. Thermo-responsive actuating means comprising a shell forming a chamber having its one end closed by a bellows and its opposite end closed by a plate, a block of heat insulating material formed with a central bore and having its 35
- one end face castellated, a projection on said plate and extending into said bore, means enterable in said bore for securing said block to said projection, an annular container rotatably mounted on the opposite end face of said block, means for clamping said container in place, a tube, said last-mentioned block face being formed with a segmental slot having a peripheral width materially greater than the diameter of said tube, said tube having its one end mounted in said slot and connected to said container, its intermediate portion wound about the periphery of said block, and its opposite end inserted between castellations of said block and received in an aperture in said plate. 80 85 90
7. Thermo-responsive actuating means comprising a shell forming a chamber having its one end closed by a bellows and its opposite end closed by a plate, a block of heat insulating material mounted on said shell and having its end adjacent said shell castellated, an annular container rotatably mounted on the opposite end face of said block, means for clamping said container in place, a tube, said last-mentioned block face being formed with a segmental slot having an axial depth slightly greater than the diameter of said tube and a peripheral width materially greater than the diameter of said tube, said tube having its one end mounted in said slot and connected to said container, its intermediate portion wound about the periphery of said block, and its opposite end inserted between castellations of said block and received in an aperture in said plate. 95 100 105
